UNITED STATES PATENT OFFICE.

HERMANN FAHLENBERG, OF PANKOW, NEAR BERLIN, GERMANY, ASSIGNOR TO
RICHARD A. HANSEMANN, OF BERLIN, GERMANY.

AUTOMATIC SAFETY DEVICE FOR CINEMATOGRAPHIC APPARATUS.

Application filed December 6, 1919. Serial No. 343,097.

To all whom it may concern:

Be it known that I, HERMANN FAHLENBERG, a citizen of Germany, residing at and whose post-office address is Pankow, near Berlin, Pestalozzistrasse 29, Germany, have invented certain new and useful Improvements in Automatic Safety Devices for Cinematographic Apparatus, of which the following is a specification.

10 If, in cinematograph apparatus a bad, glued joint or an irregularity of the film shifting device gives rise to a snapping of the film it will be pulled out of its guides by the motor and, if the apparatus continues 15 working, it will be crumpled up into a ball so as to become unfit for further use. The film is also liable to be snapped by getting jammed and stuck in some part of its system of guides.

20 The object of the present invention is to provide a guard or safety device for cinematographic apparatus which, in the case of the film being broken or getting jammed in its guides, automatically opens the circuit 25 through which current is supplied to the electric lantern and the motor by which the film mechanism is driven. This is accomplished by arranging a loaded member to be supported by the film and to move in one 30 direction or the other and switch off the current when the film snaps or becomes stuck.

A manner of carrying out the invention is illustrated in the drawing which represents an interior view of a part of a cinematographic apparatus in which the film 35 and the safety device are in evidence.

40 A mercury switch *a* of a known type is revolvably mounted on a pivot *i* within the range of a rod *b*. The rod *b* carries two adjustable stops *h*, *h*¹ and is suspended on a pulley *c* from the endless film *e* which travels over the fixed pulleys *d*¹, *d*², *d*³ . . . *d*¹⁰. The rod is also loaded at the bottom with a weight *g*.

45 Now if the film snaps at *f*, or at any other point, the rod *b* loaded with the weight *g* is pulled downward in its guide and its stop *h* strikes against the holder of the mercury switch *a* causing the switch to be swung

down about its pivot *i*. This causes the 50 globule *k* of mercury to flow into the inclined right hand end of the tube of the mercury switch thus severing the connection between the positive and negative terminals. Through these terminals the current is supplied to the electric lantern and motor of the apparatus, these parts being omitted to 55 simplify the drawing.

If the film becomes stuck at any part of its guiding mechanism the film band lying 60 between the said part and the film shifting device will be pulled tauter than usual and this will result in the rod *b* being pulled upward and in the lower stop *h*¹ of the same 65 striking against the cradle or holder of the mercury switch *a*. The left end of this switch will thus be tilted down causing the globule *k* of mercury to move to the end of the tube and open the circuit.

I claim:

1. In a cinematographic apparatus having a motor driven film, a weighted member freely suspended from a loop in the film, said member being adapted to be moved in opposite directions when said loop increases or diminishes in length and a switch in the circuit of said motor normally in a closed position and adapted to be opened by the movement of said member in either direction, thereby to open the switch when the 80 film is abnormally loose or abnormally taut.

2. In a cinematographic apparatus having a motor driven film, a weighted rod suspended from the film, a switch in the circuit of said motor adapted to be directly 85 actuated by said rod, guiding members for the film, means for raising the rod and opening the switch when the film is held back by a guide member, and a member on the said rod for opening the switch when 90 the film fails to support the rod.

In testimony whereof I have affixed my signature in presence of two witnesses.

HERMANN FAHLENBERG.
